UNITED STATES PATENT OFFICE.

ROBERT H. F. SEWALL, OF NEW ORLEANS, LOUISIANA, ASSIGNEE OF ONE-HALF TO
SAMUEL F. HEASLIP, OF NEW ORLEANS, LOUISIANA.

REINFORCED-CONCRETE RAILROAD-TIE.

1,131,562.

Specification of Letters Patent.

Patented Mar. 9, 1915.

Application filed August 10, 1912, Serial No. 714,430. Renewed July 18, 1914. Serial No. 351,813.

To all whom it may concern:

Be it known that I, ROBERT H. F. SEWALL, a citizen of the United States, residing at New Orleans, in the parish of Orleans and State of Louisiana, have invented a new and useful Reinforced-Concrete Railroad-Tie, of which the following is a specification.

My invention relates to improvements in reinforced concrete railroad ties, and it is intended to provide a concrete tie so reinforced that the strains may be as evenly distributed throughout the tie as practicable, so that the tie may be especially reinforced beneath the rails, so that the tie may automatically tend to center itself relative to the track and may resist tendency to lateral displacements in general, and so that the tie may be made as of light and cheap construction as possible and yet may be of the desired strength and resistance, both to vertical and compressive longitudinal strains.

The purpose of the invention is also to provide means for supporting the rails against lateral displacement relative to the ties, and for preventing the holding-down bolts from being accidentally vertically withdrawn.

My invention will be understood by reference to the accompanying drawings, in which the same parts are indicated by the same reference symbols throughout the several views.

Figure 1 is a plan view of a single tie, showing segments of the rails mounted thereon; Fig. 2 is a front view of the tie with the roadbed removed, part of the tie being shown in central longitudinal section, the rails above the same being shown in section; Fig. 3 shows a sectional elevation through that portion of the tie immediately below the rail, and shows means for securing the rail against lateral movement on the tie; Fig. 4 shows a section along the line 4-4 of Fig. 2, and looking in the direction of the arrows; Fig. 4^a shows a similar view to Fig. 4, except that the wire truss member is substituted for the metal plate truss member of Fig. 4; and Fig. 5 shows a section along the line 5-5 of Fig. 2, and looking in the direction of the arrows.

The tie 1, mainly composed of concrete, has its central section in the form of a V, flattened at the bottom as at 2 in Figs. 4 and 4^a; this portion of the tie being of con-

siderably greater maximum depth than width, and the bottom of this V-shaped central portion is inclined upward in each direction so as to form a blunt wedge adapted to be pressed into the roadbed in the center of the track. This deep wedge-shaped central portion of the tie merges toward the ends of the tie into a flat rectangular shape 3, such as is shown in Fig. 5. These rectangular ends of the tie are preferably of greater breadth than depth, so that they may have a broad bearing surface upon the roadbed. Thus the central portion of the tie tends to cut into the roadbed and to resist any lateral pressure on the rails, while the rectangular ends of the tie serve to support the tie on the roadbed near the ends, and to prevent the tie from being forced down into the roadbed.

The upper portion of the tie near its ends may be provided, as at 4, with raised portions having shoulders 4' to engage the tie supporting blocks, as will be hereinafter described.

In order to provide an efficient reinforcing means for a tie of the shape just described, I provide suitable truss members, such as 5 and 6 of Fig. 2, or 5^a of Fig. 4^a, which are connected together by suitable tie rods 7 and 8.

In Figs. 2 and 5, I have shown in the rectangular end members 3 of the tie the inverted V-shaped truss members 6, while in the wedge-shaped center of the tie, I provide a V-shaped truss plate 5 and 5^a as shown in Figs. 2, 4 and 4^a. The rods are connected to the end truss plates as shown in Fig. 5, and then pass into notches in the central truss plate 5, as shown in Figs. 2, 4 and 4^a, forming a framework having rods 9 crossing beneath the rails, as shown in Fig. 2. This metal framework is, of course, put in place before the tie is molded, and the little trusses 5 and 6 hold the rods in place while the concrete is becoming set.

It may be desirable instead of the central truss plate 5 to use a heavy wire truss 5^a, looped, as shown in Fig. 4^a, the said loops of the wire truss being adapted to receive the rods 7 and 8 as shown in Fig. 4^a. Obviously the small end trusses may also be of wire, if preferred.

It will be noted that by having the end trusses of inverted V-shaped form, and the central trusses of upright V-shaped form, a

larger number of upper rods 7 may be used than of the lower rods 8. In practice I have shown four of the upper rods and only one of the lower. Now these upper rods reinforce the tie against breaking in two, due to tensile strains, while the lower rod tends to reinforce the tie against compressive strains, such as any jar or pressure on the track may cause, so that this particular arrangement of trusses and rods enables the tie to be adequately reinforced against all compressive and tensile strains.

In order to provide suitable means for holding the screw spikes in engagement with the concrete tie, I provide soft metal expansion sockets 9, see Fig. 3, which are placed in position before the cement is poured in. These expansion sockets are oval in shape and larger toward the bottom, so as to prevent their being pulled out of the cement after it is set, and on the interior, these expansion sockets may be provided with screw-threaded bores, adapted to receive the screw threads 12' on the ends 12 of the bolts 11. These screw threads may be formed in the expansion socket 9 by molding the same about a screw spike of somewhat less diameter than the screw-threaded end 12 of the screw spike 11, or the bore may be smooth, so that the said screw spike may be screwed down firmly into said soft metal expansion socket, expanding the same in every direction against the surrounding wall of cement. These soft metal screw sockets are expansion sockets, in that the tapering, oval, bulbous shape expands in every direction against the surrounding concrete wall when the screw spike is inserted.

The rails may be secured to the cross ties in any convenient way, but I prefer the construction shown in Figs. 1, 2 and 3, in which 15 represents a wooden block resting on the top of the concrete tie and giving the desired resiliency to the structure. Above this block 15 is a metal plate 17 having its upper surface serrated, as at 21, to engage similar indentations on the side plates 18, which are caused to fit snugly against the flanges at the base of the rail, as shown in Fig. 3, and then are clamped in place and held down by the heads of the bolts 11.

The several plates 15, 17 and 18 are perforated, as at 16, to permit the insertion of the tie bolts 11. The upper plate 18 is so perforated as to permit a slight longitudinal adjustment of the plate 18 relative to the shank 13 of the tie bolt, so that the nose of said plate may be brought into close adjustment with the flange 19 of the rail 20, thus permitting standard ties to be conveniently used with various sizes of rails.

It will be noted that the supports for the rails are mounted immediately above the crossing of the reinforcing rods 7 and 8, as shown in Fig. 2, thus securing the best re-

sults against compressive and tensile strains, while the general tendency of all strains will be compression due to the peculiar wedge shape of the tie.

It will be obvious that various modifications might be made in the herein described apparatus, and in the construction, combination and arrangement of parts which could be used without departing from the spirit of my invention.

Having thus described my invention, what I claim and desire to secure by Letters Patent of the United States is:—

1. A concrete railroad tie having shallow rectangular ends, and a deep wedge-shaped central portion having its bottom tapering upward toward said ends, substantially as described.

2. A concrete railroad tie having shallow rectangular ends, and a deep wedge-shaped central portion having its bottom tapering upward toward said ends, with reinforcing rods inclined upward from the bottom of the ends of the tie to the central portion thereof, and downward from near the top of the ends of said ties to the central portion thereof to strengthen said tie against compressive and tensile strains, substantially as described.

3. A concrete railroad tie having shallow rectangular ends, and a deep wedge-shaped central portion having its bottom tapering upward toward said ends, with inverted V-shaped trusses mounted in the rectangular ends of the tie, and an upright V-shaped truss mounted in the wedge-shaped central portion of said tie, with rods crossing each other and extending substantially throughout the length of the tie, and connecting the bottom of one V-shaped truss member with the top of the next and vice versa, substantially as described.

4. A concrete railroad tie having shallow rectangular ends, and a deep wedge-shaped central portion having its bottom tapering upward toward said ends, with inverted V-shaped trusses mounted in the rectangular ends of the tie, and an upright V-shaped truss mounted in the wedge-shaped central portion of said tie, with a plurality of rods connected to the bottom of the inverted V-shaped trusses at the ends of the tie and passing over the top of the V-shaped truss in the center of the tie, and a less number of rods leading from the top of the inverted V-shaped trusses in the ends of the tie to the bottom of the V-shaped truss in the center of the tie, whereby to reinforce the tie against compressive and tensile strains, substantially as described.

5. A concrete railroad tie having shallow rectangular ends, and a deep wedge-shaped central portion having its bottom tapering upward toward said ends, with inverted V-shaped trusses mounted in the rectangular

ends of the tie, and an upright V-shaped truss mounted in the wedge-shaped central portion of said tie, with a plurality of rods connected to the bottom of the inverted 5 V-shaped trusses at the ends of the tie and passing over the top of the V-shaped truss in the center of the tie, and a single rod leading from the top of the inverted V-shaped trusses in the ends of the tie to the 10 bottom of the V-shaped truss in the center of the tie, whereby to reinforce the tie against compressive and tensile strains, substantially as described.

6. A concrete railroad tie having inverted 15 V-shaped trusses mounted in the ends of the tie, and an upright V-shaped truss mounted in the central portion of said tie, with rods crossing each other and extending substantially throughout the length of the tie, 20 and connecting the bottom of one V-shaped truss member with the top of the next and vice versa, substantially as described.

7. A concrete railroad tie having inverted V-shaped trusses mounted in the ends of the 25 tie, and an upright V-shaped truss mounted in the central portion of said tie, with a plurality of rods connected to the bottom of the inverted V-shaped trusses at the ends of the tie and passing over the top of the V-shaped 30 truss in the center of the tie, and a less number of rods leading from the top of the inverted V-shaped trusses in the ends of the tie to the bottom of the V-shaped truss in the center of the tie, whereby to 35 reinforce the tie against compressive and tensile strains, substantially as described.

8. A concrete railroad tie having shallow ends, and a deep central portion having its bottom tapering upward toward said ends, 40 with inverted V-shaped trusses mounted in the ends of the tie, and an upright V-shaped truss mounted in the central portion of said tie, with a plurality of rods connected to the bottom of the inverted V-shaped trusses, 45 at the ends of the tie and passing over the top of the V-shaped truss in the center of the tie, and a single rod leading from the top of the inverted V-shaped trusses in the ends of the tie to the bottom of the V-shaped 50 truss in the center of the tie, whereby to

reinforce the tie against compressive and tensile strains, substantially as described.

9. A reinforced concrete tie having a metal reinforce composed of a central V-shaped truss, two end trusses, a plurality of reinforcing rods passing over the central truss and diverging downwardly, their ends anchoring in the lower portions of the two end trusses, and a single reinforcing rod passing under the bottom of the central truss and diverging upwardly with its ends anchored in the end trusses, substantially as described.

10. A reinforced concrete tie having a metal reinforce composed of a central V-shaped truss, two end trusses, the central truss being of greater depth than the end trusses, a plurality of reinforcing rods passing over the central truss and diverging downwardly, their ends anchoring in the lower portions of the two end trusses, and a reinforcing rod passing under the bottom of the central truss and diverging upwardly with its ends anchored in the two end trusses, said rods crossing at points directly below the rail-carrying portions of the tie, substantially as described.

11. A reinforced concrete tie having a metal reinforce composed of a central V-shaped truss, two end trusses, a plurality of reinforcing rods passing through the central truss near the upper edge thereof and diverging downwardly, their ends anchoring in the lower portions of the two end trusses, and a single reinforcing rod passing under the bottom of the central truss and diverging upwardly, with its ends anchored in the two end trusses, respectively, said rods crossing at points directly below the rail-carrying portions of the tie, and said plurality of rods being spaced farther apart at the ends than in the center thereof, substantially as described.

In testimony that I claim the foregoing as my own, I have hereunto affixed my signature in the presence of two witnesses.
